PALLET MAKING JIG

Irving Dumm III, 8297 Oak Knoll Drive, Roseville,
Calif. 95678, and Robert A. Wilson, 8821 Etiwanda
Ave., Etiwanda, Calif. 91739

Filed Aug. 28, 1970, Ser. No. 24,747

Term of patent 14 years

Int. Cl. D8—99

U.S. Cl. D54—1

Fig. 3

Fig. 4

Fig. 5

FIG. 1 is a front elevational view of a pallet making jig, showing our new design;

FIG. 2 is an elevational view of one end, the opposite end being substantially similar in appearance;

FIG. 3 is a rear elevational view;

FIG. 4 is a top plan view;

FIG. 5 is a sectional view, taken on the line 5—5 in FIG. 3; and

FIG. 6 is a front perspective view.

We claim:

The ornamental design for a pallet making jig, as shown and described.
